UNITED STATES PATENT OFFICE.

JOHN WILL MADISON, OF REIDSVILLE, NORTH CAROLINA.

SPEED GOVERNOR FOR INTERNAL-COMBUSTION ENGINES.

1,409,115.

Specification of Letters Patent.

Patented Mar. 7, 1922.

Application filed October 7, 1920. Serial No. 415,426.

To all whom it may concern:

Be it known that I, JOHN WILL MADISON, a citizen of the United States, residing at Reidsville, in the county of Rockingham and

5 State of North Carolina, have invented certain new and useful Improvements in a Speed Governor for Internal-Combustion Engines, of which the following is a specification.

10 This invention relates to speed governors for tractors and the like.

The object of the invention is to provide a gas engine governor so constructed that the engine may be set to run at any desired 15 speed within its limit and automatically retained at such speed under all conditions.

Another object is to provide such an attachment which may also be manually controlled when desired.

20 Another object is to provide an attachment of this character equipped with connected automatic and hand controlled levers provided with means for yieldably holding them in adjusted position.

25 With these and other objects in view, the invention consists in certain novel features of construction as hereinafter shown and described and then specifically pointed out in the claim, and in the drawings illustrative 30 of the preferred embodiment of the invention.

In the accompanying drawing;

Figure 1 represents a side elevation of a portion of a tractor engine with this improved attachment shown applied.

Fig. 2 is an enlarged side elevation of the attachment detached.

Fig. 3 is a detail plan view of the governor proper, and,

40 Fig. 4 is a detail transverse section thereof taken on the line 4—4 of Fig. 2.

The attachment constituting this invention comprises a frame 1 in the form of a plate having longitudinally spaced transversely extending slots 2 therein which are 45 designed to receive two of the cylinder head bolts for connecting the frame to the engine, it being of course understood that these bolts are first removed and then replaced after passing them through said slots 2.

Extending laterally from one side edge of the frame 1 at opposite ends thereof are two arms 3 carrying at their free ends bearings 4 in which is rotatably mounted the 55 governor shaft 5. This shaft 5 extends be-

yond the outer edges of the arms 3 and carries at one end a governor driving pulley 6 which is driven from the engine fan belt and at its other end has a set collar 7 for 60 taking the thrust of the governor shaft.

Mounted on the shaft 5 are the spring carried collars 8 and 9 of the governor, collar 9 being fixed to the shaft by a set screw while collar 8 is free to slide on the shaft 65 and is provided with an annular groove 12 to receive one end of a control lever 20 hereinafter to be described. The collars 8 and 9 are connected by the usual flat leaf springs 10 on which are mounted the governor 70 weights or balls 11.

A shaped plate 13 is secured at one end to the engine and at its other end is connected with a bracket arm 14 on frame 1 as is shown clearly in Fig. 3. A bell crank 75 lever which will be herein termed the automatic control lever is shown at 20 and is fulcrumed on lever 15 the free end of the short arm of the said lever 20 being engaged with the groove 12 in collar 8 so 80 that said lever will be controlled by the sliding movement of said collar on the governor shaft as will be hereinafter more fully described.

The lever 15 has its upper end offset inwardly as shown at 16 to adapt it to be positioned between the governor shaft 5 and the plate 13. A bolt 17 extends through the upper end of lever 15 and through a transversely arranged slot 18 in the plate 13 and a coiled spring 18 is mounted on the bolt between lever 15 and the nut on the bolt and exerts its tension to hold said lever frictionally engaged with the plate so that the lever may be adjusted at any desired position and yieldably held in adjusted position by this spring.

95 The bell crank lever 20 carries a rearwardly extending arm 21 having attached to its free end a counterbalance weight 22 to 100 assist in returning the lever to normal position after it has been actuated. The free end of the long arm of the lever 20 has a ball and socket connection shown at 23 with the carbureter valve not shown for a purpose presently to be described.

A reach rod 19 connects the upper end of lever 15 with another lever 24 mounted on a plate 25 which is fastened to the engine near the driver's seat. This plate may be 110 fastened in any suitable manner, a bracket 26 being here shown for connecting it to the

engine. The plate 25 has a transversely extending arcuate slot 27 in its upper end through which passes a bolt 28 similar to the bolt 17 which connects lever 15 to plate 13. This bolt 28 passes through lever 24 intermediate its ends and has positioned thereon a coiled spring 28^a between the head of the bolt and lever 24 so as to frictionally hold said lever in engagement with plate 25 adapting it to remain in adjusted position after it has once been placed or set in such position.

From the above description it will be obvious that a gas engine equipped with the attachment constituting this invention may have the speed thereof controlled both manually and automatically and the driver may after setting the machine to run at the desired speed leave it so set and the governor will automatically maintain the tractor or other apparatus on which the engine is mounted at the set speed under all conditions.

It is of course understood that when the attachment is set by moving the levers 24 and 15 at the position desired for certain speed these levers operating through lever 20 to open or close the carbureter valve, more or less, that the governor will operate to maintain the valve at the set position. When the speed exceeds a certain limit the governor balls 11 will move outwardly in the ordinary manner of a centrifugal governor moving the collar 8 inwardly and thereby actuating lever 20 to slightly close the carbureter valve and when the engine slows down these balls 11 will move inwardly reversing the direction of the collar 8 and lever 20 to open the carbureter valve to its initial position.

Should it be desired for any reason to manually change the speed of the engine the driver may readily do so by actuating the hand control lever 24 which through the reach rod 19, lever 15 and lever 20 will operate the carbureter valve for supplying more or less gas to the engine. 45

The preferred embodiment of the invention is disclosed in the drawings and set forth in the specification, but it will be understood that any modifications within the scope of the claim may be made in the construction without departing from the principle of the invention or sacrificing any of its advantages. 50 55

What is claimed is:

An attachment of the class described comprising two plate like brackets adapted to be mounted at points remote, each having a lever pivoted at one end to one end of the plate and provided at its other end with an arcuate transversely arranged slot, each lever having a lateral extension yieldably mounted in the slot of the plate on which it is mounted, a rod connecting the levers, a centrifugal governor mounted adjacent one of said brackets, and having means for connection with an engine drive shaft, a bell crank lever fulcrumed on the lever of the bracket adjacent the governor and having one end engaged with the sliding member of the governor and the other provided with means for connection with the carbureter valve which supplies fuel to the engine, and means connected with said bell crank to assist in returning it to normal position after actuation. 60 65 70 75

In testimony whereof, I affix my signature hereto.

JOHN WILL MADISON.
